LIFT CONTROL FOR AIRCRAFT

Alfred C. Loedding, Dayton, Ohio

Application April 18, 1945, Serial No. 588,938

2 Claims. (Cl. 244—42)

1

This invention relates to a lift control for an airfoil and more particularly to a device that may be adjusted to change the effective lift of an airfoil.

An object of this invention is to provide an attachment for an airfoil, which attachment is adjustably mounted to thereby control the effectiveness of the airfoil by spoiling in various degrees the smooth flow of the air currents in the proximity of an airfoil.

Another object of this invention is to provide an adjustable lift control device extending along at least a portion of the leading edge of an airfoil, such as the wing of an airplane, which device may be adjusted into position so as to lengthen the effective size of the airfoil to increase the lift or it may be adjusted into a position to stabilize the lift for use while cruising or it may be adjusted into a position to stall the effectiveness of the lift.

Another object of this invention is to provide a device whereby the characteristic of the lift-angle attack curve may be altered at the will of the pilot.

Another object of this invention is to provide a lift control that may be attached to the airfoil of now existing aircraft so that the lift characteristic of the aircraft may be adjusted at the will of the pilot to satisfy various conditions of flight.

Other objects and advantages reside in the construction of parts, the combination thereof and the mode of operation, as will become more apparent from the following description.

Referring to the drawings, Figure 1 is a schematic top plan view of an airplane showing the lift control device.

Figure 2 is a fragmentary cross sectional view of an airfoil and a cross sectional view of the lift control attachment taken substantially on the line 2—2 of Figure 1.

Figure 3 is a cross sectional view of an airfoil showing a lift control built into the airfoil.

Figure 4 is another cross sectional view of an airfoil showing another modification of a lift control device built into the leading edge of the airfoil.

Figure 5 is another modification, showing a lift control device that may be projected out through the leading edge of an airfoil, to thereby control the lift of the airfoil.

Figure 6 is a lift angle of attack curve, showing the characteristic of the lift of an airfoil as influenced by the lift control device.

Figure 7 is another fragmentary cross sectional

2

view taken substantially on the line 7—7 of Figure 1 to show the control mechanism for actuating the lift control device.

Figure 8 is another fragmentary cross sectional view disclosing another modification of a lift control device.

It seems that according to the theory of aerodynamics as now understood, there are at least two factors influencing the lift of an airfoil.

One of these is the pressure created on the underside of the airfoil, which may account for twenty-five to thirty-three percent of the lift of the aircraft, this being a relative value and is influenced by various factors influencing the operation of the airfoil. Another factor that influences the lift of an airfoil is the flow of the air parallel to the upper surface of the airfoil. If the airfoil is properly designed and the flow of air is not spoiled, this force may account for sixty-seven to seventy-five percent of the lift of the airfoil. This lift is generally referred to as resulting from Bernoulli's Theorem. This may be put into the following very general equation $PV = Q$, where P represents the pressure, V the velocity of the airstream and Q the energy. This equation omits a number of factors that are not deemed necessary to be set forth at this time. The energy, according to Bernoulli's Theorem, remains the same. If the energy remains the same and the velocity increases, obviously the pressure must decrease. By obtaining a high velocity air stream flowing parallel to the wing surface without turbulence and without eddy currents, the air pressure upon the upper side of the wing can be made to approach zero. As soon as the smooth air flow over the top of the airfoil is disturbed, the velocity parallel to the airfoil is reduced, thereby increasing the air pressure resulting in a reduction in the airfoil lift. This theory is utilized in the device disclosed herein to control the lift of the airfoil.

The formation of ice on the leading edge of an airplane quickly destroys the lift of the aircraft by disturbing the air stream over the top of the wing or airfoil. It is not the weight of the ice that causes the airplane to fail. It is the disturbance of the air flow that causes a crack-up. Airplanes have been equipped with what is sometimes referred to as "spoilers" on the leading edge of the wing; but these spoilers have been fixed. They have not been adjustably mounted. The device disclosed herein utilizes an adjustable lift control extending along at least a portion of the leading edge of the airfoil, as will

appear more fully from the detailed description that follows.

Attempts have been made to adjust the lift on thin airfoils by providing an airfoil wherein the entire forward portion is adjustable. The length of the airfoil, as measured along the line of intersection of a transverse plane intersecting the airfoil, greatly exceeds the thickness of the airfoil. The effective lift of the adjustable portion of the prior adjustable airfoils constitutes a large percentage of the total lift of the entire airfoil. The adjustment of such an airfoil presents numerous problems in that the forces required to adjust such an airfoil are extremely great, resulting in numerous mechanical difficulties.

In the preferred embodiment and in each of the modifications the lift control is confined to the leading edge of the airfoil. This lift control is located in the area of the airfoil that develops a small percentage of the total lift of the entire airfoil. In the preferred embodiment and in each of the modifications, the lift control has been limited to a zone that is very small. The length of the airfoil, as measured along the line of intersection of a transverse plane intersecting the air foil, is much less than the maximum thickness of the airfoil. This results in easy control of the airfoil.

If it is found desirable to spoil the lift of the airfoil, only a slight upward movement of the lift control will cause eddy currents developing at the leading edge of the airfoil. It is a characteristic of airfoils that if eddy currents start at the leading edge, the air passing over the airfoil will be turbulent along the entire top edge of the airfoil. For example, it has been found that a small rivet head on the surface of the airfoil will start eddy currents, resulting in irregular flow of air to the rear of the rivet over the entire surface located to the rear of the rivet head. This clearly demonstrates that a small adjustable spoiler will greatly reduce the lift on the upper side of an airfoil. It is not necessary to adjust or change the contour of a larger portion or zone along the leading edge of the airfoil.

Referring to the drawings, the reference character 10 indicates the fuselage of an airplane having a pair of wings 12 provided along the leading edge thereof with a lift control 14. As may best be seen by referring to Figure 2, the wing 12 is provided with an extension 16 along the leading edge that may support a tubular member 18 having fixedly attached thereto a pair of deflecting plates 20 and 22 that cooperate to form a sharp edged lift control assembly. The tubular member 18 is adjustably mounted in an arcuate portion formed by member 16, which may be attached to the leading edge of a conventional airfoil.

As clearly shown in Figure 2, this lift control assembly may be in the position A or adjusted into the position B or adjusted into the position C or in any number of other positions between the limits indicated by A and C. When the lift control assembly is adjusted into the position C, it, in effect, lengthens the effective upper surface of the wing, thereby enlarging or increasing the lift of the wing. When it is adjusted into the position B, the full line position, the lift control is adjusted into a position suitable for cruising. When the lift control assembly is in the position B, the lift of the wing or airfoil is slightly more than sufficient to maintain the aircraft at a constant altitude. Under this condition, a sudden change of angle of attack would cause a rise. In ascending and at any other time

that it is desirable to increase the lift of the wings, the lift control assembly is adjusted towards C, to thereby increase the lift of the airfoil or wing.

5 One of the outstanding features of this device is the ability to reduce the effect of rising currents or gusts in the cruising attitude of the airplane. The position of the lift control would be position B, which is set to provide just slightly 10 more lift than what is required. This setting B would tend to reduce serious increase in loads on the air frame and vertical displacements of the aircraft that may cause serious discomfort on the part of the occupants and heavy concentrated cargo loads of freight on cargo airplanes.

15 By adjusting the lift control so that the lift is merely sufficient to sustain the load, maximum efficiency as far as power is concerned is then obtained. If the lift of the airfoil is excessive, 20 other forces are required to counteract the excessive lift, thereby reducing the efficiency of the aircraft. The shifting of the airplane from one level to another eventually results in a loss of energy and thereby loss of efficiency. When 25 the lift control is in the position B, it presents a sharp leading edge that increases efficiency of the airfoil over a similar airfoil having a blunt leading edge. Due to the sharpness, the effect of drag, due to compressibility at high speeds, is reduced.

30 In landing, the lift control is adjusted into the position C. The lift control remains in this position until the pilot levels off, when the lift control should be adjusted into the position A. This 35 should take place when the elevators are brought unto full "up" position, that is, the stick is brought to the rear. As a matter of fact, the maximum could be provided whereby the raising of the elevators to the full "up" position automatically 40 raises the lift control into the A position. By raising the lift control into the A position while the airplane is off the ground, a large increased drag is created due to the stall. This will cause a very short run effecting a spot landing, which 45 would be necessary with aircraft carriers, et cetera. The description of the adjustment of the lift control in the C position for landing takes care of normal atmospheric landing conditions.

If the air conditions are gusty or bumpy, the 50 lift control would remain in position B, adjusted so as to provide just sufficient lift so as to get a very high degree of lateral stability. The overall lift in this position will be less; but due to the high wind velocities under such conditions, the 55 relative ground speed will still be low. Again, when the pilot levels off and raises the elevators to the full "up" position, the lift control is raised into the A position, so as to create a stall, thereby shortening the run.

60 The lift control assembly may be provided with an arm or extension 30, as shown in Figure 7, connected to a link 32, having its opposite end connected to a lever 34. This lever 34 is pivotally attached to a suitable support at 36. The handle 65 38 is lowered, the lift control is raised so as to reduce the lift of the wing or airfoil. If the handle 38 is raised, the lift of the wing is increased, tending to cause the airplane to ascend.

Referring to Figure 6, there is shown an aero- 70 dynamic curve where lift has been plotted as ordinates and the angle of attack as abscissa. From this curve it can be readily seen that when the lift control assembly is in the position B, the curve levels off, as indicated by the horizontal line B in Figure 6. When the lift control is in

the position C, the lift is increased, so that it follows the curve C. When the lift control assembly is raised into the position A, the lift is decreased and follows the dotted line A. The full line represented by the designation "normal," shows the lift of the wing or airfoil in the absence of a lift control being attached thereto.

This lift control assembly is not necessarily confined in its use to cruising speed, ascending and stalling. It may also be used in stormy weather.

Furthermore, the cylindrical or tubular member 18 may be used as a passage for exhaust gases and thereby the lift control assembly may be used as a defroster. The exhaust gases need not necessarily be confined to the tubular member. The exhaust gases may also flow between members 20 and 22, so as to supply heat to a tip of the lift control assembly, thereby melting the ice where it would first form, in the absence of a defrosting device. Furthermore, the lift control assembly, if exhaust gases are not used, may house an electrical heating element for supplying heat to the lift control assembly, which heater element functions as a defroster.

As clearly seen in Figure 1, the lift control device does not extend throughout the entire length of the leading edge of the wing or airfoil. The length of the lift control depends upon the design of the wing or airfoil. It depends upon the effectiveness of the design. It depends upon the purpose for which the aircraft is to be used, the type of load, flying conditions, etcetera. The length of the lift control is a matter of choice, depending upon the purpose of the aircraft. Likewise, the size is a matter of choice. It need not be very large. Rivet heads have been found to reduce the lift by creating eddy currents across the upper surface of an airplane wing. Thus, it is readily seen that the lift control may be quite small.

In the modification disclosed in Figure 3, the lift control has been built into the leading edge of the wing or airfoil 40. The leading edge of the wing 40 has been provided with an arcuate cavity 42 that receives a tubular member 44. Member 44 is adjustably mounted in the cavity 42, so as to prevent oscillation of member 44 about the longitudinal axis thereof. A pair of members 46 and 48 extend forwardly from the tubular member 44, so as to provide a sharp edge extending along at least a portion of the leading edge of the airfoil. The lift control assembly may be raised or lowered in a manner similar to that described in connection with Figure 2.

In the modification disclosed in Figure 4, the airfoil 50 has been provided with a longitudinally extending recess 52. One side 52a of this recess is arcuate and the other side 52b is straight. A lift control member 60 is provided with a curved surface 62a, that has a radius of curvature compatible to the radius of curvature of the adjacent airfoil, a curved surface 62b and a straight surface 62c. Member 60 is pivotally mounted at 64 to the airfoil 50 and may be oscillated about the pivot 64 so as to be in the full line position B shown in Figure 4 or raised into the dotted position A, or the dot-dash position C.

The full line position B may be referred to as the cruising lift control position. The dotted position A may be referred to as the stalling position and the dot-dash position C may be referred to as the ascending or lifting position.

In the modification disclosed in Figure 5, a lift control 70 is mounted in a suitable slot 72 in the

leading edge of the airfoil and is mounted for reciprocating movement. When member 70 is withdrawn into the airfoil, the airfoil operates as a normal airfoil without a lift control. When member 70 is projected through the slot 72 so as to extend beyond the airfoil, member 70 functions as a spoiler to reduce the lift of the airfoil. Member 70 may be controlled in any suitable manner.

10 Although the control shown in Figure 7 and described in connection with the preferred embodiment shown in Figures 1 and 2 is manually controlled, the lift control may be automatically controlled, especially when flying through stormy

15 weather. For example, a sudden increase in temperature along the leading edge may operate a suitable thermostatic control mechanism to raise the lift control so as to reduce the lifting power of the airfoil. Such warm air currents are in 20 all probability the result of upwardly directed air streams intersecting the path of the airplane. In order to counteract the rising air currents, the lift of the airfoil is reduced, so as to maintain the course of the airplane on an even level.

25 In Figure 8 another lift control mechanism has been shown. The airfoil 80 has been shown in dotted lines and has attached thereto an adjustable flap 82 adjustably attached to the airfoil 80 by a hinge 84. Member 82 carries at its leading edge a second flap 86 pivoted at 88 and slidingly engaging the airfoil 80. Members 82 and 86 cooperate to form a lift control. This lift control may be adjusted into the A position, when it functions as a spoiler, and into the C position, 35 both shown in dotted lines.

30 Although the preferred embodiment of the device has been described, it will be understood that within the purview of this invention various changes may be made in the form, details, proportion and arrangement of parts, the combination thereof and mode of operation, which generally stated consist in a device capable of carrying out the objects set forth, as disclosed and defined in the appended claims.

35 Having thus described my invention, I claim:

40 1. A lift control assembly for use on an airplane having wings provided with a leading edge that is curved, said lift control assembly including an extension having an arcuate recess extending parallel to the front edge of the wing, said extension being mounted along the leading edge of the wing and being provided with a curvature merging into the curvature of the wing, a tubular member rotatably supported in the arcuate recess,

45 and a pair of deflecting plates fixedly attached to the tubular member, said deflecting plates cooperating to form a sharp lift control edge so that when the tubular member is rotated so as to adjust the deflecting plates into a position

50 whereby the effective length of the upper surface of the wing is increased, the lift of the wing is increased; when the tubular member is adjusted into a position whereby the edge formed by the deflecting plates is directed slightly upwardly so that the upper plate forms a well defined angle with the upper surface of the wing, a drag is created; and when the tubular member is adjusted into a selected position between the aforementioned positions, the lift of the wing may be such that its lift is slightly more than sufficient to maintain the airplane at a constant altitude.

55 2. A lift control assembly for use on an airplane having wings provided with a leading edge that is curved, said lift control assembly including an extension having an arcuate recess extending

parallel to the front edge of the wing, said extension being mounted along the leading edge of the wing and being provided with a curvature merging into the curvature of the wing, a cylindrical member rotatably supported in the arcuate recess, a pair of deflecting plates fixedly attached to the cylindrical member, said deflecting plates cooperating to form a sharp lift control edge, and means for adjusting the cylindrical member so that the deflecting plates may be adjusted into position whereby the effective length of the upper surface of the wing is increased to thereby increase the lift of the wing; the deflecting plates may be adjusted by said adjusting means into another position whereby the edge formed by the deflecting plates is directed slightly upwardly so that the upper plate forms a well defined angle with the upper surface of the wing to thereby create a drag; and the deflecting plates may be adjusted into position by said adjustable means intermediate the aforementioned positions, which position is selected to create a lift of the wing

such that the lift is slightly more than sufficient to maintain the airplane at a constant altitude.

ALFRED C. LOEDDING.
